STEAM ENGINE OPERATION EFFICIENCY DEVICE

Application filed May 1, 1928. Serial No. 274,328.

This invention relates to reciprocating steam engines equipped with valve-gear which permits variation of cut-off at the will of the operator, and has for its object the provision of an audible indicating device, by following the dictates of which, the operator is enabled to so adjust the cut-off of the engine that the same will be worked to the best advantage of power and economy for any and all speeds within its range, or any predetermined part thereof. This device may be applied to such engines in any service, as stationary, marine, or locomotive. The audible signal may be operated by any of various means, as steam, electricity, mechanical, compressed air &c. The said audible signal may be arranged to sound when the relation of speed to cut-off is correct and be silent when incorrect, or, conversely, be silent when said relation is correct and sound when incorrect. To show and describe all such possible combinations is undesirable and unnecessary here, therefore the following description and drawings are confined to a form of this device suitable for application to a locomotive, in which electricity is chosen to represent the sounding medium, and the sound to take place when the relation of speed to cut-off is not correct within pre-determined limits. This invention is based on the well known principle that any engine can exert maximum power at any particular speed (R. P. M.) of the crank-shaft, only when the gear is set to effect cut-off at one particular place of the piston stroke, that if steam is cut off either earlier or later than at that particular place, the power output will be less than maximum.

Referring now to the drawings, Fig. 1 is an elevational view partly sectional and partly diagrammatic of a device constructed according to this invention, Fig. 2 is a left hand, and Fig. 3 is a right hand view of Fig. 1, but each, for the sake of clearness,

showing only a few parts. Fig. 4 is a sectional view in more and enlarged detail, of the end of lever 11. Fig. 5 shows an alternative.

Referring now more particularly to the drawings, enclosed in a suitable housing as 1 attached to any desired part of the locomotive, as to the frame member 2, is a speed controlled mechanism of any desired type, size or kind, and designated here broadly by 50 the Figure 3, its function being to control one side of an electric contact-breaker in accord with the R. P. M. of the crankshaft. This speed controlled mechanism 3 is rotated by connection in any suitable manner 55 to an axle or wheel of the engine, or other part which revolves in fixed proportion to the crankshaft, the drawings showing it connected by helical gears 4 and flexible drive 5 to the friction wheel 6, which is carried by 60 yoke 7 pivoted at the fixed point 8, and pressed against the rim of the wheel 9 by the spring 10. Engaging with and operated by said speed controlled mechanism 3, is lever 11, free to swing by the action of said 65 mechanism 3, on fixed point 12. Carried by lever 11, but insulated therefrom, and preferably adjustable therein, are two contact pieces 13 and 14, which latter are electrical- 70 ly connected, preferably through switches 75 15 and 16, one each, to one side of two electrically operated sounding devices, located in or near the engine cab, of different tone, as indicated by the electric bells 17 and 18 80 and their differing size.

The other terminals of the bells 17 and 18 are connected to a cut-out switch 19 preferably controlled by the throttle operating apparatus, indicated diagrammatically by the 85 throttle lever 20, in such manner that the device is cut out when the throttle is closed and cut in when the throttle is opened as indicated in Fig. 1 and cut-out 19 is connected to a source of electrical energy represented at 90

21, the other side of which is grounded as seen.

Also pivoted to fixed pin 12, and free to swing thereon is another lever 22, the end of which, terminating preferably with a roller, is held to engagement, by spring 23, with the working face of a cam as 25. On this lever 22 is formed a lug 24 which projects across lever 11 between the contact pieces 13 and 14, and forming or constituting the other contact piece of the two electric circuits, as lever 22 is grounded as indicated, or may be directly connected with generator 21. It can now be readily seen that, the concerned switches being closed, if lever 22 be swung to the right, lug 24 would touch contact 14, completing the circuit and ringing bell 18, while if permitted to move to the left, lug 24 would touch contact 13, completing the other circuit and so cause bell 17 to sound instead; and conversely, if lever 22 is held stationary and lever 11 moved upwards, contact 14 would touch lug 24 ringing bell 18, and if moved downwards, contact 13 would likewise complete the circuit which sounds bell 17; in the position shown in the drawing both circuits are broken and neither bell can sound; in short, when relative movement takes place between levers 11 and 22 beyond the limits provided by the respective adjustments of contact pieces 13 and 14, one or the other of the bells rings. Cam 25, the working face of which controls the position of lever 22, is secured to grooved pulley 26, by means of nut 27, locating pin 37 determining the correct relative position of cam and pulley, which, as a unit, are free to pivot around the fixed pin 28, in one direction by the action of cable 30, and in the other direction by means of the spring 31 when permitted by the slackening of cable 30. One end of said cable 30 is securely attached, see 29, to pulley 26, and the other is likewise securely attached to any convenient part of the cut-off controlling mechanism, such as to the valve-gear tumbling shaft lever 32, through the means of the grooved quadrant 33 fastened to said lever 32 as seen, the cable being secured at 34. This lever 32 is connected to the reach-rod, not shown, in the usual way, and is swung to the right or left around the centre 35 to reverse the engine or vary the cut-off at the will of the engineman in the usual manner. It will now be clear that the position of lever 22 is entirely within the control of the engineman by means of the cut-off controlling mechanism.

In the drawings, lever 32 is shown in full gear position for one direction of the locomotive, and by moving said lever so that its centre line coincides with line 36, full gear position for running in the opposite direction will be attained, the vertical line indicating mid-gear position.

The principle underlying this invention,

which will, by the foregoing, now be readily recognized, centres around an electric circuit which carries a sounding device and a movable contact-breaker, one terminal or point of which is in the control of and operated by the cut-off controlling means, and the other is in the control of apparatus operated by the speed of the engine.

Cam 25 is so constructed and located on the pulley 26 that, when lever 32 is in the position shown, the lever 22 is held by the cam in its extreme right position; moving said lever 32 to position 36, rotates cam 25 to the right (clockwise) bringing the other high spot on the cam—seen across the opening—into line with the contact end of lever 22, and again holding it in the extreme right position. Placing lever 32 in its central position brings the lowest point of cam 25 into line with said contact end of lever 22, and thus permits spring 23 to move said lever 22 to its extreme left position. The intervening portions of the working face of the cam 25 are shaped in accord with the desired combination of cut-off and engine speed, using data obtained, preferably, from dynamometer tests, and a curve showing angular movement of lever 11 vs. speed, and on completion are such that, if speed α causes lever 11 to swing through γ degrees, then, when lever 32 is placed in position to give the corresponding correct cut-off, cam 25 will permit lever 22 to move γ degrees also, thus keeping lug 24 from contact with either 13 or 14; this holds true for the entire speed range. From the foregoing it will be readily understood that, when in operation, so long as lever 32 is placed in the correct position for the speed of the engine, no bell will sound; and conversely, with lever 32 in any position, a change of speed beyond the allowable limits, either higher or lower (determined by the adjustment of contacts 13 and 14), will cause either 13 or 14 to touch lug 24 so ringing bell 17 or 18 respectively, thus indicating to the engineman that he is to move lever 32 to get the lug out of contact and so stop the bell, and the direction in which he must do so is indicated by the high or low tone of the alarm, according to which bell is rung, preferably high tone for shortening the cut-off and low tone for lengthening same.

It will also be clearly seen, that not only does this device, as described above, enable the engineman to manipulate the cut-off controlling means to the utmost advantage at all times, but it also permits him to do so without taking his eyes from the road and signals ahead.

The operation of this device, when constructed as described above, can be well understood by here describing an imaginary run on a locomotive so equipped. On arrival at the roundhouse to take out the engine, the

5 engineman will find this apparatus in the positions shown, except that lever 32 will be in its central position, and consequently cam 25 will be presenting its lower side towards lever 22, and this lever 22 will be, by influence of its spring 23, in its extreme left position touching the cam: lug 24 will be pressing against contact 18 and, consequently, if lever 11 were made solid it would be compelled to 10 compress the spring—or lift the weights as the case may be—of mechanism 3, thereby setting up a strain in the levers 11 and 22, to prevent which, lever 11 may be made in two parts, as seen in Fig. 4, to permit flexure 15 whenever speed controlled mechanism 3 and cam 25 are not in corresponding working positions; the spring-actuated plunger seen in Fig. 4 presses against the flat base of the outer section of lever 11 and holds it in the 20 position shown under normal operating conditions, and in other circumstances permits said outer section to pivot in either direction around pin 38, slightly depressing the plunger aforesaid, which, on the deflecting force being removed, will return said outer section to the normal position seen in the drawings. No bells will be ringing because 25 switches 15, 16 and 19 will be open, and turbo-generator 21, where used, may not be working. He is ready to move and goes 30 backward and forward as necessary to set back on to his train, all in an absolutely normal manner, there being no noise from the bells as switch 15 and 16 are still open although 35 19 has been alternately opened and closed as the throttle was worked.

Ready to start, he puts the cut-off controlling means in full gear position as seen in Fig. 1 and closes switches 15 and 16, then 40 opens the throttle, closing switch 19; still no ring as lug 24 is clear of both 13 and 14. The engine moves and mechanism 3 commences to operate. Having a train of maximum tonnage, the throttle is pulled wide 45 open and the engineman takes his accustomed place, with head probably out the window watching the road ahead and signals. The train gathering speed, mechanism 3 commences to lift lever 11, and, on reaching the 50 speed limit for full gear operation, contact 14 touches lug 24 ringing bell 18, which should be one of distinct yet pleasing sound, and preferably higher in tone than the other, indicating that he should "link up" as it is 55 termed, or shorten the cut-off. Without taking his eyes from the road, the engineman shortens the cut-off in response to the bell signal, a notch at a time, until the ringing ceases, and the engine still exerts maximum 60 effort; what has happened is that by shortening the cut-off, the cam 25 has been slightly rotated, presenting a lower part toward lever 22 which, actuated by spring 23 has been moved to the left accordingly, and so 65 broken the contact of lug 24 with 14. With

speed increasing, lever 11 is further lifted and again 14 connects with 24, again sounding 18, a warning which is again answered by the engineman shortening the cut-off further until ringing again ceases, by the 70 corresponding further rotation of cam 25 and movement of lever 22. This series continues at longer and longer intervals until the maximum speed possible with that load is attained when ringing will cease entirely 75 and silence prevail until speed shall decrease. Running now on to an up grade, the speed commences to drop, and lever 11 to move downward; upon reaching the low limit for that cut-off, contact piece 13 touches lug 24 and bell 17 now sounds, which, being of lower tone than 18, indicates that the engineman should "drop her down" a little, or lengthen the cut-off, which he accordingly does, still with his eyes on the road, until 80 the ringing stops, and so on until speed ceases to drop. Assume now that a level piece of road has been reached and along which the engine could haul the train at a speed higher than is desired; attaining the 85 desired speed limit and capable of running faster, contact 14 again connects with lug 24 sounding 18; merely linking up until the bell ceased would only increase the speed beyond the desired limit, so the engineman takes one 90 of two possible courses; either he closes the throttle a little until the engine is getting only enough to maintain that speed, or, preferably, he cuts out bell 17 by opening switch 15, and links up until the desired speed is 95 just maintained, thus working with maximum economy. Unfavorable grade again causing the speed to drop, switch 15 is closed again and normal operation again prevails. On reaching a stopping place or a down 100 grade where steam is not required, the throttle is closed, opening switch 19, and the reverse lever can be put in any position without any sound from the bells. For moving about the yard, 15 and 16 may be opened, 105 thus permitting the throttle to be used without sounding the bells.

Modern locomotives seldom do any serious work when running backwards, indeed, data useful for constructing the working face of the cam for backward running is often not available, consequently it may be desired in many cases to arrange for this device to indicate when running forward only; in such cases the only change necessary from the foregoing will be to construct cam 25 with that part coming opposite lever 22 when running backward, preferably with the same radius as at the mid-gear position, as seen at the lower part of Fig. 5. Another modification 115 of this device without departing from the nature thereof, would be to construct it with only one electric circuit and bell: either one may be retained, preferably, that which indicates the cut-off is too long. When one cir- 120 125 130

cuit only is employed, levers 11 and 22 may be formed as one unit, having no relative movement, as seen in bellcrank 11—22 in Fig. 5, the single contact piece being located at the 5 end of the unit and forming the part which touches the cam, the circuit breaker thus consisting of the said contact piece and the cam, as shown. When operating the device thus modified, the bell will ring when speed increases as before explained; but when speed 10 is decreasing no bell will sound, and the engineman must keep lengthening the cut-off to just clear of the ringing position, to obtain maximum power. It will be recognized that, 15 with this arrangement, the contact piece will be just clear of the cam in normal running position, also that the unit 11—22 being entirely in the control of the speed controlled mechanism 3 will have no use for spring 23 which 20 accordingly is dispensed with. Altho the primary object of this invention is, as before stated, to provide means to enable the engine operator to correctly manipulate the cut-off without having to use his eyes, it is obvious 25 that the sound principle described within may, without departing from the nature of this invention, be employed in combination with a sight indicator, after the manner of Pullman car berth, steamship state room or 30 hotel room sound-sight indicators, devices too well known to require illustration or further description here. Moreover, friction wheel 6 may, if desired, be released from contact with wheel 9 when not required, by the 35 provision of any suitable means, such as shown dotted in Fig. 1 where, upon admitting air or other pressure medium to the cylinder above the piston, the latter exerts force on the extension of yoke 7, causing pivoting on 8, 40 thus raising wheel 6.

Furthermore, it is to be understood, while I have herein shown and described preferred embodiments of this invention, the same is nevertheless susceptible of many minor modifications in the form, proportion, and relative arrangement of the several parts; and I accordingly reserve the privilege of adapting all such legitimate changes as may be fairly embodied within the spirit and scope of the invention as claimed.

What I claim is:—

1. A locomotive, in combination with a device which can be cut in and cut out by manipulation of the engine throttle, and which, 55 when predetermined relation exists between the speed of the engine and the position of the cut-off controlling means, co-operates with the operator's sense of hearing to apprise him of that fact.
- 60 2. On a locomotive, the combination with the cut-off controlling means and a revolving member of said locomotive, of sound producing means, and means co-operating with said cut-off controlling means revolving member 65 and sound producing means, to, when in op-

eration, create sound when the speed of the engine is greater than predetermined limits allow for the then position of the said cut-off controlling means, audibly indicate in a distinctly different manner when the speed of the engine is less than pre-determined limits allow for the same position of the said cut-off controlling means and maintaining silence when the speed is within said pre-determined limits.

3. A locomotive, in combination with a device which, when the speed of the engine is greater than predetermined limits allow, and also when the speed is less than predetermined limits allow for the then position of the cut-off controlling means, co-operates with the operator's sense of hearing in manner individually distinguishable to apprise him of the fact.

4. On a locomotive, the combination of 85 electrically operated sound producing means, electric circuit-breaking means, a source of electric energy, suitable connecting means for the same, any desired controlling means for the passage of said electric energy independent 90 of and additional to said circuit-breaking means, and means, co-operating with said circuit-breaking means, with the cut-off controlling means of the locomotive and with a revolving member of said locomotive, whereby the control of said circuit-breaking means is vested jointly in the said cut-off controlling means and revolving member by virtue of its speed, the whole co-acting to audibly indicate when pre-determined relation exists between 95 the speed of said revolving member and the position of said cut-off controlling means.

5. A structure as specified in claim 4 in which the said controlling means for the passage of electric energy, shall include means for cutting the device into and out of action by manipulation of the engine throttle.

6. A structure as specified in claim 4 in which the positive and the negative elements of said electric circuit-breaking means are 100 movable independently.

7. A structure as specified in claim 4 in which the positive and the negative elements of said electric circuit-breaking means are movable independently, means co-operating 110 with one of such elements and with said cut-off controlling means whereby said element is positioned by manipulation of said cut-off controlling means, and means co-operating with the other such element and with said 120 revolving member whereby the position of said other element is determined by, and varies with, the speed of said revolving member.

8. A structure as specified in claim 4 in which the positive and the negative elements of said electric circuit-breaking means are movable independently, a suitably formed cam which functions to control the position of one of said elements, and means co-operating 125 with said cam and with said cut-off con- 130

trolling means, whereby the functions of said cam are controlled by the said cut-off controlling means.

9. A structure as specified in claim 4 in which the positive and the negative elements of said electric circuit-breaking means are movable independently, a suitably formed cam which functions to control the position of one of said elements, a wheel to which said 5 cam is attached, and means co-operating with said wheel and with the cut-off controlling means whereby said wheel, carrying said cam, is moved about its centre by manipulation of said cut-off controlling means.

10. A structure as specified in claim 4 in which the positive and the negative elements of said electric circuit-breaking means are independently movable, a suitably formed cam which functions to control the position of 10 one of said elements, a wheel to which said cam is attached, a flexible member one end of which is connected to a suitable member of the cut-off controlling means, and the other is wrapped around said wheel and then 15 attached to it, whereby movement of said suitable member revolves said wheel in one direction by pulling with said flexible member, and in the other direction by permitting action by a spring operatively connected with 20 said wheel for that purpose.

11. A structure as specified in claim 4 in which the positive and the negative elements of the said electric circuit-breaking means are independently movable, means for positioning one of said elements by manipulation of the cut-off controlling means, a suitable 25 mechanism such as used for governors and speedometers which functions by virtue of its speed, means co-operating with such mechanism and with the other element of said circuit-breaker to position said other element in 30 accord with the speed of said mechanism, and means co-operating with said mechanism and with said revolving member to enable said 35 revolving member to drive said mechanism in accord with the speed of said revolving member.

12. A structure as specified in claim 4 in which the positive and the negative elements 40 of said electric circuit-breaking means are movable independently, means for positioning one of said elements by manipulation of the cut-off controlling means, a suitable mechanism employed to position the other 45 element of said circuit-breaking means, flexible driving means operatively connected with said mechanism and with a circular member engaging with said revolving member.

13. A structure as specified in claim 4 in which the positive and negative elements of 50 said electric circuit-breaking means are movable independently, means for positioning one of said elements by manipulation of the 55 cut-off controlling means, a suitable mecha-

nism employed to position the other element of said circuit-breaking means, flexible driving means operatively connected with said mechanism and with a properly proportioned friction disc carried in a suitable frame pivoted to a fixed part of the engine and held in contact with a wheel of the locomotive by suitable force exerting means. 70

14. A structure as specified in claim 4 in which the positive and the negative elements of said circuit-breaking means are independently movable, means for positioning one of said elements by the manipulation of the cut-off controlling means, a suitable mechanism employed to position the other element of 75 said circuit-breaking means, driving means operatively connecting said mechanism with said revolving member, and means for cutting in and cutting out the operation of said mechanism by said revolving member. 80

15. A locomotive, in combination with a device which, when the cut-off is not correct within predetermined limits for the then speed of the engine, functions to so inform 85 the operator, and which ceases to so function when the cut-off is changed correctly and remains correct. 90

16. A locomotive or other fluid pressure engine, in combination with a device which, when predetermined relation exists between 95 the speed of the engine and the position of the cut-off controlling means, functions to inform the operator of that fact, and which ceases to so function when such predetermined relation does not exist. 100

17. On a locomotive, the combination with the cut-off controlling means and a revolving member of said locomotive, of means intermediate and co-operating with said cut-off controlling means and with said revolving 105 member, which, when predetermined relation exists between the speed of the engine and the position of the said cut-off controlling means, co-operates with the operator's sense of hearing to apprise him of that fact, and which ceases to so inform him when said predetermined relation does not exist. 110

18. A structure as specified in claim 16, wherein said device can be cut in and cut out at the will of the operator. 115

19. A structure as specified in claim 16, wherein said device includes operative interconnecting means between said cut-off controlling means, a revolving member of the engine and suitable sound producing means. 120

20. A locomotive, in combination with a device which, when the speed of the engine is greater than predetermined limits allow for the then position of the cut-off controlling means, functions to so inform the operator, and which fails to so function when the speed is within predetermined limits. 125

21. A locomotive, in combination with a device which, when the speed of the engine is less than predetermined limits allow for 130

the then position of the cut-off controlling means, functions to so inform the operator, and which fails to so function when the speed is within predetermined limits.

- 5 22. A locomotive, in combination with a device partly electrical and partly mechanical in nature which, when predetermined relation exists between the speed of the engine and the position of the cut-off controlling means, functions to so inform the operator, and which ceases to so function when such predetermined relation does not exist.
